AWNNG APPARATUS

Henry K. Sandell, Chicago, Ill.

Application February 9, 1931, Serial No. 514,491

13 Claims. (Cl. 156—44)

This invention relates in general to awning apparatus and more particularly to awnings and apparatus for manipulating awnings, screens, and the like.

5 An important object of the invention is to provide a power driven or manipulated awning and such a device of simple and durable construction.

Another important object of the invention is to provide such a device which may be controlled 10 from a remote location, singly and also in banks or groups where several such devices are used such as on sections of, or on entire sides of buildings.

Another important object is to provide a compact power unit which may be readily attached 15 to awnings and the like and at either one of the ends thereof for manipulating the awning.

Other objects and advantages of the invention will be apparent as it is better understood from 20 the following description, which, taken in connection with the accompanying drawings, discloses a preferred embodiment thereof.

Referring to the drawings:

Figure 1 is an elevational view of the upper 25 portion of a window equipped with awning apparatus embodying my invention.

Fig. 2 is an end elevational view of the apparatus shown in Fig. 1 and viewing the apparatus from the right.

30 Fig. 3 is a similar view showing the awning raised or folded and illustrating the action of the control or reversing means.

Fig. 4 is an enlarged elevational view of a preferred form of manipulating unit partly broken 35 away to show details of construction.

Fig. 5 is a section taken substantially on line 5—5 in Fig. 4 further illustrating the arrangement of the parts of the manipulating unit.

Fig. 6 is a horizontal section taken substantially 40 on line 6—6 in Fig. 4, illustrating the driving connection between the manipulating unit and an awning reel.

Figs. 7, 8, 9 and 10 are changed position views 45 diagrammatically illustrating the functions of a preferred form of reversing switch or control means.

Fig. 11 is a wiring diagram showing the various electrical connections, and,

50 Fig. 12 is a plan view of one of the parts clearly illustrating the preferred form thereof.

To illustrate the invention I have shown the upper portion of a window 11 equipped with awning apparatus including an awning 12, an awning frame 13 which in the present embodiment

includes a swinging frame 14 and a reel 15, and a manipulating or control unit 16.

The window obviously may represent any framed opening or the like to which an awning, screen, or the like may be attached.

5 The awning 12 may be any fabric or other covering such as may be used for covering an opening to exclude light, water, and the like, and such as may require opening and closing, or raising and lowering. In the present embodiment a fabric awning or covering 21 is shown.

The frame 13 includes the swinging frame 14 preferably formed of a rod or tube formed to U shape and having its ends 22 formed to extend through or otherwise pivot in suitable bearing brackets 23 secured to the frame of the framed opening by means of screws 24 or in any suitable manner, and in the present embodiment includes the reel 15. The reel 15 illustrated is a core 24' provided with a shaft 25 which preferably 15 extends through the core 24' and end bearing brackets 26 and 27 in which the reel is rotatably supported. The awning or covering 21 is suitably secured to the core 24', of the reel 15 and is folded on or wrapped about the core for raising or folding upon rotation of the core and similarly lowering is effected by reverse rotation 20 of the core 24'.

The control mechanism or manipulating unit 16 includes a power unit 31 and a control mechanism 32 for controlling the power unit 31.

The power unit 31 includes power means such as an electric motor 33, a drive shaft 34, and transmission elements such as a worm gear 35 suitably secured to the drive shaft 34 and a worm 36 similarly secured to a motor shaft 37. The motor 33 is or may be suitably mounted on a bearing bracket 38 which bracket may also provide end bearings 41 and 42 for the drive shaft 34. A spacing collar 43 may be assembled on the shaft 34 for aligning the worm gear 35 between the bearings 41 and 42, (Fig. 6) and these bearings may be formed to provide sockets 44 and 45 for receiving an end of the shaft 25.

45 The driving connection between the shaft 25 and the drive shaft 34 may be effected in any suitable manner and to accomplish this connection I have shown a tongue or key and slot connection, the ends of the shaft 25 being transversely slotted to provide slots 46 and 47 and the ends of the shaft 34 being formed to provide keys or tongues 48 and 49. The duplicate end formations make possible the assembly of the manipulating unit 16 at either one or the other 50 55

of the ends of the shaft 25 as operating conditions may require.

The control of the power unit 31 in the present embodiment is effected by controlling the electric current supplied to the motor 33. This is accomplished by means of a contact switch 50, a snap switch 51 (Figs. 1, 4, 5 and 11) and a magnet 52. The snap switch 51 includes a block 40 of insulating material pivotally mounted on a shoulder screw 53 having threaded engagement in a boss 54 formed on the bracket 38 and carrying oppositely disposed contact strips 55 and 56 together forming a pivoted fork 60, and a contact strip 57 having its opposite ends bent laterally to provide contact stops 58 and 59 and suitably mounted on a block 61 of insulating material which is in turn suitably secured to the bracket 38.

The magnet 52 includes a coil 65 of suitable proportions wound on a core 66 and is arranged to move or lift an armature plate 67. The armature plate 67 is preferably a substantially rectangular plate (Fig. 12) having a projecting tongue 68 and provided with lugs 69 by means of which the plate 67 may be pivotally mounted on a lug 71 formed on the bracket 38 by means of a pin 72 extending through the lugs 69 and 71. Movement of the plate 67 is limited in one direction by the core 66 of the magnet and in the opposite direction by a stop lug 73 formed on the bracket 38.

Snap movement of the pivoted fork 60 is effected by means of a crank 74, a pin 75 mounted in the block 40, and a tension spring 76 connecting the crank 74 and the pin 75. The crank 74 is rotatably mounted in a bearing 77 formed on the bracket 38 and is longitudinally located or adjusted in the bearing 77 by means of a thrust collar 78 and an operating handle 79 as indicated, (Fig. 4). The operating handle 79 is preferably formed to provide a crank similar to the crank 74 except that it is of larger proportions. It is an object of this invention to effect reversals of the power unit 31 as an incident to the movement of the awning and to provide one means for accomplishing this. A strand 81 of suitable material is attached to a handle portion 82 of the crank 79 and to a suitable fitting, such as an adjustable collar 83, (Figs. 2 and 3) mounted on and secured to the swinging frame 14. The strand 81 through the crank 79 effects a reversal of the operation of the power unit 31 at one extremity of the range of movement of the awning and the handle portion 82 of the crank 79 engages the awning or swinging frame 14 to effect an opposite reversal at the other extremity as will be later described.

The contact switch 50 may be any suitable device for making electrical contact such as a push button and is electrically connected to energize the magnet coil 65 of one or more of the manipulating units through a suitable circuit such as the wires 91, 92, and 93, (Fig. 11) connected to line wires 94 and 95. The line wire 94 is also connected to the contact strip 57 and to an armature 96 of the motor 33 and the line wire 95 is also connected to the plate 67 through a suitable ground connection on the bracket 38.

To illustrate the action of the fork 60 I have shown the various active positions assumed by the fork in operation (Figs. 7, 8, 9 and 10). The fork 60 being set for operating movement of the motor 33 in one direction (Fig. 7) released and in the corresponding running position (Fig. 8), set for movement of the motor in the opposite

direction (Fig. 9) and released to effect running in the corresponding direction (Fig. 10).

The opposite ends of a field winding 97, (Fig. 11) of the motor 33 are connected to the contact strips 55 and 56 and the circuit through the winding of the armature 96 is completed through a wire 98 and a flexible contact member 99 suitably mounted on the block 61 and arranged to make contact with the plate 67 when said plate is lifted by the magnet 52. The position of the crank 74 and fork 60 (Fig. 7) corresponds with the lowered position of the awning (Fig. 2) the succeeding operating movement of the manipulating unit 16 is to raise the awning to the position shown (Fig. 3). The crank 74 and spring 76 are urging the fork 60 toward the left (Fig. 7). When contact is established at the contact switch 50 which obviously may be located in any remote position, the coil 65 is energized which effects a lifting of the plate 67 to complete the circuit through the armature 96, the wire 98, the contact member 99, and the plate 67, and release the fork 60. When contact at the switch 50 is broken the plate 67 is released to complete a circuit through the stop contact 58 of the strip 57, the contact strip 55, the field winding 97, the contact strip 56, and the plate 67 as indicated (Fig. 8). As the awning approaches the end of its elevating or folding movement, the swinging frame 14 engages the handle portion 82 of the crank 79 which is disposed in the path of movement of the swinging frame 14 and reverses the snap switch or positions the crank 74 to move the fork 60 into the position shown (Fig. 9) thus opening the previously established connections and stopping the motor 33. Another contact at the push button 50 releases the fork 60 to complete similar running circuits (Fig. 10) except that current is directed through the field winding 97 in an opposite direction thus effecting a reversal of the action of the manipulating unit 16. At the end of lowering movements of the awning 12 the strand 81 reverses the snap switch or positions the crank 74 to move the fork 60 into the position shown (Fig. 7), as above described.

The mechanism may be protected from the elements by a suitable sheet metal cover 101.

The manipulating unit 16 being compact and relatively small may be readily transported and detachably assembled for use and at either one of the ends of an awning in accordance with existing conditions and requirements.

It is thought that the invention and many of its attendant advantages will be understood from the foregoing description, and it will be apparent that various changes may be made in the form, construction, and arrangement of the parts without departing from the spirit and scope of the invention, or sacrificing all of its material advantages, the form hereinbefore described being merely a preferred embodiment thereof.

I claim:

1. The combination with an awning and frame therefor, of power means detachably connected to said frame, circuit closing devices providing a remote control whereby said awning may be adjusted from a remote location, and means adjusted by the awning frame for adjusting said circuit closing devices to determine the direction of successive movements of the awning.

2. The combination with an awning and frame therefor, of power operating means detachably connected to said frame, circuit closing devices providing a remote control whereby said awning may be operated from a remote location, and me-

chanical connecting devices whereby said circuit closing devices are adjusted as an incident to movement of the awning frame to determine the direction of successive operating movements thereof.

5 3. The combination with an awning, of an electrically operable power means arranged for raising and lowering the awning, and means including an automatically operable circuit adjusting device providing a control for said power means whereby the power means may be actuated to effect successive positional adjustments of the awning, the circuit adjusting device being subject to movement of the awning.

10 4. The combination with an awning and frame therefor, of an electrically operable power means mechanically arranged for adjusting the awning, and means including circuit adjusting devices automatically operable by means of the awning frame and providing a control for said power means whereby the power means may be actuated to cause successive positioning movements of the awning.

15 5. The combination with an awning and frame therefor, of power means arranged for raising and lowering the awning, and means associated therewith for controlling and determining the action of said power means, said means including a circuit closing device arranged for adjustment by means of the awning frame.

20 6. The combination with an awning and frame therefor, of power means arranged for positioning the awning by means of the frame thereof, means associated therewith whereby the power means is supported adjacent and coupled to the awning frame, and means including a circuit adjusting mechanism and a remote control device therefor whereby the awning may be adjusted from a remote location, the circuit adjusting mechanism being associated with the power means and controlled by movement of the awning frame.

25 7. Awning apparatus comprising, an awning, a frame therefor including a reel, a power operating unit associated with said reel, and means controlled by said frame for controlling the power operating unit and including a remote control device.

30 8. Awning apparatus comprising, an awning, a frame therefor including a reel, a power operating unit operably connected with said reel, means actuated by the awning for adjusting directional action of said operating unit, and means for releasing said last mentioned means to effect either raising or lowering movement of the awning.

9. Awning apparatus comprising, an awning, a frame therefor including a reel carried on a reel shaft, and a power operating mechanism for adjusting said awning including a power element, a drive shaft operably connected therewith and having oppositely disposed driving connections either one of which may be engaged with the reel shaft of said frame, and means for controlling the power element.

10. An awning adjusting device comprising, a 10 motor, a drive shaft adapted for connection to an awning, transmission devices connecting said motor and said drive shaft, control means mounted adjacent said motor and arranged to control the directional action thereof, means adjusted by 15 the awning for limiting the action of said motor and means for mounting the assembly in operative relationship and in engagement with an awning.

11. An awning adjusting device comprising, a 20 motor, a drive shaft having a plurality of driving connections either one or both of which may be operatively connected with an awning, transmission devices connecting said motor and said drive shaft, a reversing mechanism arranged adjacent said motor and to control the directional action thereof, means adjusted by the awning for limiting the action of said motor and support means for mounting the assembly thereof in operative relationship and in engagement with an 30 awning.

12. Awning apparatus comprising, an awning, a frame therefor including a reel, a power operating unit arranged for mounting adjacent the frame reel and having a driving connection therewith, and switch devices mounted with the operating unit and arranged to effect raising and lowering movement of the awning alternately, said switch devices being subject between successive positioning operations to control by means 40 of an electrical connection device remotely established and electrically connected with said switch devices.

13. A mechanical operating attachment for awning apparatus comprising, a support frame, a 45 motor secured to said frame, motor control mechanism arranged adjacent said motor and to control operation thereof in accordance with predetermined positioning movements of the awning, and manually operable release means operatively 50 connected thereto whereby the control mechanism may be adjusted upon occasion to cause adjusting movements of the awning in accordance with the adjustment of said control mechanism.

HENRY K. SANDELL. 55
